WITNESS

ATTORNEY

UNITED STATES PATENT OFFICE.

ALFRED H. NIEMEYER, OF CHICAGO, ILLINOIS.

CASKET.

Application filed April 23, 1926. Serial No. 104,152.

This invention relates to certain novel improvements in caskets and more particularly to an air sealed casket box for holding the body of a person who has died of a contagious disease where the law prohibits and where it is detrimental to the physical safety to society to permit the body to be viewed from an open or uncovered casket and has for its principal object the provision of an improved construction of this character which will be economical in manufacture.

Other objects will appear hereinafter.

The invention consists in the combination and arrangement of parts to be hereinafter described and claimed.

The invention will be best understood by reference to the accompanying drawing illustrating the preferred form of construction and in which:

Fig. 1 is a top plan view of the body receiving box embodied in the invention illustrating the same removed from the casket shell.

Fig. 2 is a sectional detail view of the body receiving box taken substantially on line 2—2 of Fig. 1 illustrating the body receiving box confined in the casket shell.

Fig. 3 is a fragmentary sectional detail view taken substantially on line 3—3 of Fig. 1.

To accomplish the various objects of the invention I provide a casket shell 10 including side walls 11, end walls 12 and 12' and a bottom wall 13. The casket shell 10 includes a cover 14 comprising sectional parts 15 and 16. These sectional parts are secured to one of the side walls 11 in a manner well known in the art and are preferably covered by a suitable fabric covering also in a manner well known in the art.

The end wall 12' and the side walls 11 have recesses 17 formed in their top edge portions, as best illustrated in Fig. 2, for reasons hereinafter understood.

At this point I wish it to be understood that the shape of the casket shell, as well as the construction thereof is immaterial so far as the present invention is concerned as it will be hereinafter understood that the invention can be associated with casket shells of various sizes and shapes without departing from the spirit of the invention.

Confined in the casket shell, Fig. 2, is a body receiving box which includes metallic wall portions 18 and 19 defining the body receiving compartment 20. The wall portions 18 and 18' at the head portion of the body receiving box extend upwardly above the wall portion 19 defining together with adjacent portions of the casket shell a compartment 21 for reasons hereinafter understood. The wall portions 18 and 19 are reinforced by reinforcing strips 22 secured to these wall portions by suitable securing elements 23. In distending the wall portions in the position illustrated in Fig. 2 of the drawing it is intended that where the adjacent edges of the wall portions meet that these edges be sealed together for the purpose of providing an air tight body receiving box. The sealing of these adjacent edges can be accomplished by any one of the known methods in the art.

The upwardly extending portions 19' of the wall portions 18 and 18' define a rectangular opening 24 which permits observation of the interior of the head portion of the body receiving box. The top edge portions of the wall portions 18 and 18' define seats 25 disposed outwardly from the outer surface of these wall portions. Certain wall portions defining these seats are confined in the recesses 17 herein mentioned.

Positioned upon these supporting seats 25 is a rectangularly shaped rubber gasket 26 sealed to the supporting seats 25 through the medium of a layer of white lead 27, Fig. 2. Above this rubber gasket is arranged a glass sheet 28 which closes the opening 24 and arranged adjacent the peripheral edges of this glass sheet is a second rectangularly shaped rubber gasket 29, Fig. 2. This rubber gasket 29 is disposed between the glass sheet 28 and inwardly turned flanges 30 of a cap ring 31, as best illustrated in Fig. 2. This cap ring 31 includes depending flanges 32 which are disposed adjacent the outer surfaces 33 of the wall portions 34 defining the seats 25.

The cap ring 31 is secured in position, to compress the rubber gaskets with the peripheral edges of the glass sheet therebetween through the medium of a plurality of U-shaped clamping bolts 35 of any approved construction. These clamping bolts 35 have

end portions 36 which engage beneath the wall portions 33 defining the seats 25. The adjustable bolts 37 of these clamping bolts have their head portions 38 disposed upon the inwardly turned flanges 30. By adjusting these bolts 37 in a certain direction the cap ring will be forced down upon the gasket 29 and effectively seal the glass sheet between itself and the seats 25 thereby providing an air tight frame for the glass sheet 28.

From the description herein it will be apparent that the construction provides an air tight body receiving box for a casket shell whereby the glass sheet permits an unobstructed view of the head portion of the body (not shown) confined in the body receiving box.

In order to preserve the body (not shown) confined in the body receiving box, to prevent the growth and spread of contagious germs I preferably remove a certain amount of air from the box to form a partial vacuum therein. This is accomplished by providing an outlet valve 38^a of any approved type and attaching the hose (not shown) of a vacuum pump (not shown) thereto for the purpose. The valve is constructed on the order of a check valve which permits the exit of air but not the admission thereof.

A vacuum gauge 39 is provided for the purpose of determining the vacuum pressure within the body receiving box. This vacuum gauge when in use is supported by a suitable pet cock 39' of any approved type. This pet cock includes the usual operating handle 40 which opens communication between the vacuum gauge and the interior of the body receiving box. A second valve is provided for testing the air tight condition of the box. This second valve is indicated at 38', Fig. 2, and likewise is of any approved type. One method of testing of the air tight condition of the box is accomplished by connecting an air pump (not shown) to the valve structure 38' and submerging the body receiving box in a tank of water during the operation of the air pump. If bubbles appear it is evident that the box is not completely air tight.

The construction of the vacuum gauge as well as the valve structures has not been included in the description of the invention for the sole purpose that neither the valve structures nor the vacuum gauge constitute the essence of the present invention as it is apparent that any approved vacuum gauge as well as valve structures can be used to serve the purpose.

It is known that in most States of the Union the body of a person who has died of a contagious disease cannot be placed in an open casket of the ordinary construction for obvious reasons. Therefore it is an object of the present invention, as is evident

from the description herein, to provide a casket which includes an air sealed body receiving box for receiving the body of a person who has died of a contagious disease to permit unobstructed observation of the head portion of the body. It is also pointed out that the casket embodying the invention is one which can be used for shipping the body of a person a considerable distance. This is accomplished by reason of the fact that the body is preserved because of the air tight condition of the body receiving box.

In use the cover section 15 is preferably closed to obstruct observation of the foot portion of the body including the valve structures and the pet cock 39' and as the cover section 16 is preferably open it is intended that a suitable trimming 35' be provided to hide the rough finish of the body receiving box.

While I have illustrated and described the preferred form of construction for carrying my invention into effect, this is capable of variations and modification without departing from the spirit of the invention. I therefore, do not wish to be limited to the precise details of construction set forth, but desire to avail myself of such variations and modifications as come within the scope of the appended claims.

The invention having been set forth, what I claim as new and useful is:

1. The combination with a casket shell, of sectional covers for the shell, a vacuum body receiving box confined in the casket shell, said box including at its head portion a sight opening, and a closure frame for the sight opening, said frame including supporting seats defined by wall portions of the box, transparent sheet compressible gaskets disposed on opposite sides along the peripheral edges of the transparent sheet, a cap ring having inturned flanges disposed over one of the gaskets, and a sealing material between the other of the gaskets and the supporting seats.

2. An air sealed body receiving box including wall portions providing seats defining a sight opening, a compressible member upon the seat, sealing material between the member and the seat, a transparent member having edge portions resting upon the member, a compressible member disposed above the transparent member along the edge portions thereof, a cap ring having inturned flanges disposed above the second mentioned compressible member, and clamping members for clamping said cap ring in position to seal the transparent member between the cap ring and the seats.

3. The combination with a casket shell, of a cover therefor including individual sections, a vacuum body receiving box confined in the casket shell, said box including at its head portion a sight opening and having its

top wall at its foot portion arranged below the sight opening, a valve structure carried by said top wall and in communication with the interior of the box and adapted for connection with the hose of a vacuum indicating mechanism carried by the top wall and in communication with the interior of the box,

one of said sections of the cover concealing the sight opening when in closed position and the other of the sectional covers concealing when in closed position the valve structure and vacuum indicating mechanism. 10

In testimony whereof I affix my signature.

ALFRED H. NIEMEYER.
